US00D761833S

(12) **United States Design Patent**
Huang et al.

(10) **Patent No.:** **US D761,833 S**
(45) **Date of Patent:** **** Jul. 19, 2016**

(54) **DISPLAY SCREEN WITH GRAPHICAL USER INTERFACE OF A MENU FOR A NEWS DIGEST**

(71) Applicant: **YAHOO! INC.**, Sunnyvale, CA (US)

(72) Inventors: **Shin-Yi Huang**, Sunnyvale, CA (US); **Agnes Liu**, Walnut, CA (US)

(73) Assignee: **Yahoo! Inc.**, Sunnyvale, CA (US)

(**) Term: **14 Years**

(21) Appl. No.: **29/502,113**

(22) Filed: **Sep. 11, 2014**

(51) LOC (10) Cl. **14-04**

(52) U.S. Cl.

USPC **D14/486**

(58) **Field of Classification Search**

USPC D14/485, 486, 487, 488, 489, 490, 491, D14/492, 493, 494, 495

(57) **CLAIM**

The ornamental design of a display screen with graphical user interface of a menu for a news digest, as shown and described.

DESCRIPTION

The sole FIGURE is a detailed view of a display screen with graphical user interface of a menu for a news digest.

The broken line(s) on the display screen and text form no part of the claimed design.

1 Claim, 1 Drawing Sheet
